UNITED STATES PATENT OFFICE.

EDMOND V. ROURE, OF PHILADELPHIA, PENNSYLVANIA, ASSIGNOR OF
TWO-THIRDS TO CORNELIUS A. LANE AND JOHN L. KELLY, OF SAME
PLACE.

METHOD OF UTILIZING LIQUEFIABLE GASES IN OPERATING ENGINES, &c.

SPECIFICATION forming part of Letters Patent No. 607,662, dated July 19, 1898.

Application filed July 21, 1896. Serial No. 600,018. (No specimens.)

To all whom it may concern:

Be it known that I, EDMOND V. ROURE, a citizen of France, and a resident of the city of Philadelphia, State of Pennsylvania, have 5 invented a certain new and Improved Method of Utilizing Liquefiable Gases in the Operation of Engines, &c., of which the following is a full, clear, and exact description, reference being had to the accompanying drawing, 10 which illustrates in elevation a plant suitable for the carrying out of my invention.

My invention relates to certain improvements in the operation of engines by the direct pressure of gases or vapors from liquefiable gases—that is to say, gases which at normal temperature and under normal conditions exist as such in the form of gas or vapor and which under the influence of pressure and cold may be made to assume a liquid 20 form.

It is well known that when liquefied gas is held under pressure and subjected to the action of heat the slightest increase in temperature, as by the mere application of the 25 heat of a lamp, will raise the pressure of the gas to an enormous extent, and if released the gas passes to its normal gaseous form under great pressure and in condition to be utilized for the driving of an engine of 30 almost any character. It is usual in the use of such gases to save and to condense the same by cold, and if to be used over and over again they must be compressed again to cause them to reassume the liquid condition. The 35 engines operated by these gases are necessarily operated under extremely high pressure, often more than seven hundred pounds per square inch, and owing to the pressure and the fact that the gas is exceedingly dry 40 and hot it is almost impossible to introduce, or when introduced to gain any beneficial results from, ordinary lubricants in the engine. As now practiced grease or oil distributers of very delicate and special construction are 45 employed, and owing to the danger of leakage of the high-pressure gases these distributers must be made very strong and require the very best workmanship to prevent leakage. Another difficulty is that the gas, being very

dry and hot, will carry away some of the 50 grease and cause it to accumulate in the condenser-pipes; but the most serious objection is that when the gas comes into contact with the grease or oil it will heat the latter not to a sufficient extent to change it into vapor, but to cause it to absorb and become charged with the gas, and so form new chemical compounds of different properties which remain in the cylinder of the engine in the 55 form of tar, which obstructs piston and valves. 60

There are some gases, such as chlorid of methyl, which are natural lubricants and which may be used directly as motor agents, and if so used the engine will not need any additional lubricating agent; but these substances 65 cannot be used to advantage from an economical standpoint owing to their high point of liquefaction and because of the great amount of caloric which they absorb before a sufficiently high working pressure can be attained. 70

The object of my invention is to overcome all of these objections by employing a mixture of gases of such nature that two very important advantages are gained—first, the increase of actual working pressure over the pressure which may be attained by the use of a single gas under the same conditions of use, and, second, the lubrication of the engine without auxiliary lubricating substances by 80 the employment in the working mixture of a gas having known lubricating properties. If, for instance, a gas is used that can be liquefied at high pressure and low temperature, as carbon dioxid, and a gas, such as 85 chlorid of methyl, which is a natural lubricant, the desired result is attained, as the two gases mix together and the lubricating properties of the chlorid of methyl always keep the engine properly lubricated. 90

In order that the method of operation about to be described may be more readily understood, reference is now had to the accompanying drawing, which illustrates an apparatus suitably arranged for carrying my invention 95 into effect.

In the drawing, A represents the original receiver or boiler, heated, as by the gas-

burner *s*, shown beneath it. The gases to be employed are introduced into the boiler *A* and under the action of the heat produced by the burner are forced through the pipe *a* into the valve-chamber of the cylinder *B* behind the piston-head and after acting thereon escape through the pipe *b* to the coil *c*, situated in a tank *C*, filled with cold water. Becoming liquefied and cooled by the process the liquefied gas then passes through the pipe *e* into the cylindrical receptacle *D*, in the lower part of the same, the valve *e'* in said pipe being normally open to permit the flow of the liquid into said receptacle.

15 Above the cylinder *D* is a cylinder *E*, mounted in such position that all or the greater portion thereof shall be above the liquid-level of the boiler *A*. From the upper portion of the boiler *A* to the upper portion of the cylinder *D* extends a pipe *d*, having a valve *d'*, which is normally closed, and from the upper portion of the cylinder *E* to the lower portion of the cylinder *G* extends a pipe *f*, having a valve *f'*, also normally closed. From the lower portion of the cylinder *E* to the upper portion of the boiler *A* extends a pipe *g*, having a valve *g'*, also normally closed. From the boiler *A* extends a vertical pipe *i*, leading to a pressure-gage *h*, and from the cylinder *E* extends 30 a vertical pipe *i'*, leading to a pressure-gage *h'*. The two vertical pipes *i* *i'* are connected by a pipe *k*, having a valve *k'*, which is normally closed. On the boiler and cylinders are gages *H* to ascertain the liquid-levels in these receptacles, and on the pipe *e*, at the exit end of the condenser *C*, is a pressure-gage *h²*, the various gages being so arranged that the different pressures and liquid-levels at different points may be at all times visible.

35 40 In conducting the operation all the valves in the apparatus except the valves in the pipes *a*, *b*, and *e* are closed, and in the boiler *A* I proceed to mix in the liquid state carbon dioxid with about one-third to one-half of its 45 volume of chlorid of methyl, the latter gas having affinity for and absorbing a considerable proportion of the carbon dioxid, the first and natural result being that the pressure of the gases in the boiler is reduced in much the 50 same manner as it would be if a mixture of ammonia-vapor and water were employed. The mixture is then heated in the boiler by the gas-burner *s* or by any proper application of heat, and the temperature is raised 55 from the normal to about 90° Fahrenheit, the chlorid of methyl when thus heated rejecting all of the carbon dioxid which it has absorbed and the pressure becoming equal to what it would if pure carbon dioxid were employed. 60 The chlorid of methyl, however, also passes in a gaseous form, and when the carbon dioxid passes off to the engine through the pipe *a* the chlorid of methyl will travel with it, the two gases being mechanically mixed and both 65 of them acting on the piston of the engine. After acting on the piston both gases are con-

ducted by the pipe *b* to the condenser-pipes *c*, where they are cooled to a temperature proper for their recondensation to liquid form, which, however, is accomplished only 70 by the exercise of considerable pressure, the pressure in the condenser when carbon dioxid is employed being about eight hundred pounds and the direct working pressure exerted by the gases on the piston of the engine 75 will be about fifteen hundred pounds, so that with a back pressure of, say, eight hundred pounds from the condenser the active working pressure will be the difference between the two, or about seven hundred pounds. 80 This is the case where pure carbon dioxid is employed; but with the addition of the chlorid of methyl a new step takes place which very materially increases the working pressure of the engine by reducing the back pressure 85 thereon, and this is due to the fact that as the chlorid of methyl is cooled in the condenser it reasserts its affinity for the carbon dioxid and absorbs the same, so that the pressure in the condenser is reduced considerably below 90 eight hundred pounds in much the same manner that it was reduced by the preliminary mixture in the boiler. If the reduction in pressure is, say, two hundred pounds, this same amount will be added to the working pressure 95 of the engine and the same will be raised from about seven hundred pounds to about nine hundred pounds.

Owing to the avidity with which the chlorid of methyl absorbs the carbon dioxid when the 100 two are reduced to the proper temperature this reduction of pressure may be increased to some considerable extent by properly proportioning the relative amounts or quantities of the gases and the work of the engine be 105 correspondingly augmented.

As before stated, all of the valves in the apparatus except the valves of the pipes *a*, *b*, and *e* are normally closed, and as the vapor from the boiler after operating the engine is condensed in the condenser *C* it flows through the pipe *e* until the cylinder *D* becomes partially filled with comparatively cool liquid. When it is desired to transfer this liquid to the cylinder *E*, the valve *e'* in pipe *e* is closed and the valve *d'* in pipe *d* and the valve *f'* in pipe *f* are opened. The vapor from the boiler *A* under heavy pressure then enters the upper portion of the cylinder *D* and forces the liquid therein up through the pipe *f* to the cylinder *E*, and this is continued until the desired quantity 110 has been so transferred, when the valves *d'* and *f'* are closed and the valve *e'* again opens. It follows then that the cylinder *E* contains liquid somewhat heated from its contact with the vapor and at a level above the level of the liquid in the boiler *A*. After a time the liquid in the cylinder *E* is cooled, and when the boiler *A* needs replenishing the valve *k'* in the pipe *k* is opened and the upper portion of 115 the boiler placed in communication with the upper portion of the cylinder *E*, the vapor 120

under pressure flowing from the boiler to the cylinder and equalizing the pressure in both vessels. Valve g' in pipe g is then opened, and the liquid flows by gravity from the cylinder E to the boiler A .

The engine need not at any time be stopped, as the pipes governing the flow of gas to effect the movement of the liquid are comparatively small and there is little or no decrease in pressure.

In carrying out my invention I may mix chlorid of methyl with about one-half its volume of toluene or methyl benzene, which acts in the same way with chlorid of methyl as does the chlorid of methyl with carbon dioxid, the absorbing action, however, being somewhat more thorough and complete.

If a compound mixture of carbon dioxid, chlorid of methyl, and toluene be made, a portion of the carbon dioxid will be absorbed by the chlorid of methyl and by the toluene, and a portion of the chlorid of methyl will be absorbed by the toluene. When this mixture is heated to about 90° Fahrenheit, the component gases are separated and each then exerts its full expansive power and the three gases in mechanical mixture pass through the engine and from thence to the condenser.

As the gases are cooled in the condenser the carbon dioxid is partially absorbed by the chlorid of methyl and the chlorid of methyl is partially absorbed by the toluene, so that the pressure is reduced and the active working pressure on the opposite side of the piston of the engine is augmented to a corresponding extent.

The toluene-vapors do not to any material extent contribute to the motive power of the engine, as the heat is never raised to a sufficient degree to obtain any effective pressure from the vapors, but they are useful in that with the chlorid of methyl they act as a lubricant, and, further, they absorb in the heating operation a large amount of caloric, which they carry to the cylinder of the engine and there act to maintain the heat, and consequently, the pressure, of the working gases.

Having thus described my invention, what I claim, and desire to secure by Letters Patent, is—

1. The herein-described method of utilizing liquefiable gases in the operation of engines, said method consisting in mixing with a liquefiable gas of high pressure at a given temperature, another liquefiable gas of lower pressure at the same temperature, which latter gas has an absorbing affinity for the first gas, heating said gases, conducting them through an engine to operate the same and condensing the gases, the affinity of the gas liquefiable at the higher temperature exerting itself at this stage of the process upon the other gas at a temperature higher than the point of liquefaction of the other gas.

65 2. The herein-described method of utilizing

liquefiable gases in the operation of an engine, said method consisting in mixing two or more liquefiable gases when in a liquefied or nearly liquefied condition, one of said gases being liquefiable at a temperature lower than the point of liquefaction of the other gas, the gas liquefiable at the higher temperature having an absorbing affinity for the other gas, heating the mixed gases to separate the same and to increase their pressure, conducting said mixed gases to and through an engine to operate the same, and reducing the temperature of such gases to or below the point of liquefaction of the one gas and partly absorbing by it the vapors of the other gas before that temperature is reached at which the said other gas becomes liquefied, and continuing the reduction of temperature to or below the point of liquefaction of both gases.

3. The herein-described method of producing power in engines, said method consisting in generating gas from a mixture composed of two or more liquefiable gases liquefiable under different pressures at the same temperature, and reducing the back pressure after the operation of the gases upon the piston of the engine by cooling and first liquefying one of the gases and absorbing by the said liquefied gas, the vapors of the other gas before the point of liquefaction of said other gas is reached.

4. The herein-described method of utilizing carbon dioxid and chlorid of methyl in a gas-engine, said method consisting in mixing the two gases until the carbon dioxid is partially or wholly absorbed by the chlorid of methyl, heating said gases to separate the same and increasing their pressure, conducting the gas to and through an engine to operate the same, then reducing the temperature of the gases until the chlorid of methyl is liquefied and absorbs the vapors of the carbon dioxid while the carbon dioxid is in its gaseous form and continuing the reduction of temperature until both gases are liquefied for reducing the back pressure for the purposes described.

5. The herein-described method of utilizing carbon dioxid, chlorid of methyl and toluene in the operation of an engine, said method consisting in mixing the carbon dioxid, chlorid of methyl, and toluene under pressure until the toluene partially or wholly absorbs the chlorid of methyl, and the carbon dioxid is partially or wholly absorbed by the methyl and toluene, heating the gas to separate the same and increasing their pressures, conducting said gases to and through an engine to operate the same, reducing the temperature of the gases to the point of liquefaction of the toluene, absorbing a portion of the gases of the chlorid of methyl by the liquefied toluene, continuing the reduction of temperature to the point of liquefaction of the chlorid of methyl not absorbed, absorbing a portion of

the gases of the carbon dioxid by the liquefied chlorid of methyl and continuing the reduction of temperature until the liquefaction of all the gases occurs for reducing the back pressure on the engine.

5 6. The herein-described compound for the operation of engines the same consisting of chlorid of methyl, carbon dioxid and toluene

combined in or in about the proportions specified.

In witness whereof I have hereunto set my hand this 17th day of July, A. D. 1896.

EDMOND V. ROURE.
